[57] CLAIM

The ornamental design for an edible container for confection, as shown and described.

DESCRIPTION

FIG. 1 is a top perspective view of an edible container for confection showing my new design, with the confection shown in broken lines for illustrative purposes only;

FIG. 2 is a front elevational view thereof, the rear elevational view and right and left side elevational views being substantially mirror images thereof;

FIG. 3 is a top plan view thereof;

FIG. 4 is a bottom plan view thereof;

FIG. 5 is a cross-sectional view thereof, taken on line 5—5 of FIG. 2; and

FIG. 6 is a cross-sectional view thereof, taken on line 6—6 of FIG. 3.

The characteristic feature of my design resides in the combination nuggets embedded in a cone as best illustrated in FIG. 1.
